Fig. 2.

Diagram illustrating the electrical circuit for a 'Marginal' device, labeled Fig. 2. The circuit is powered by a 1/2" rotation step. Key components include a main switch labeled 'Marginal' (224), a coil labeled '219', and a switch labeled '222'. The circuit is interconnected with numerous wires and components, including resistors and capacitors. A note on the diagram states 'Operates on 1/2" Rot. Step.'

UNITED STATES PATENT OFFICE.

RAY L. STOKELY, OF FLORAL PARK, LONG ISLAND, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

Original application filed April 20, 1921, Serial No. 462,868. Divided and this application filed March 29, 1924. Serial No. 702,710.

To all whom it may concern:

Be it known that I, RAY L. STOKELY, a citizen of the United States of America, residing at Floral Park, Long Island, in the county of Nassau, State of New York, have invented certain new and useful Improvements in Machine-Switching Telephone-Exchange Systems, of which the following is a full, clear, concise, and exact description.

This invention relates to telephone exchange systems employing machine switching and is a division of my application Serial No. 462,868 filed April 20, 1921, since issued as Patent 1,501,074, July 15, 1924.

The object of this invention is to provide an improved circuit arrangement to take care of toll calls to and from full automatic offices.

In the present system a toll operator's dial is automatically connected to a desired trunk by inserting a plug in the jack of said trunk and a supervisory lamp at the operator's position is flashed to indicate a busy condition of either the called line or an intermediate trunk group. The supervisory lamp is also lighted upon the insertion of the operator's plug in the jack of the trunk in case the distant automatic equipment is not in condition to receive dial impulses and remains so lighted until such distant equipment is ready for the impulses, or until the plug is removed from the jack at which time it is extinguished.

The principal feature of this invention, therefore, is the provision of means, at an operator's position, to indicate when the distant automatic equipment is not in condition to receive dial impulses.

Referring to the drawings, Fig. 1 shows a toll cord circuit and part of a trunk outgoing from the toll board to a full mechanical or automatic office; Fig. 2 shows an incoming selector at the full mechanical office; Fig. 3 shows a toll transmission selector repeater; Fig. 4 shows a combination toll and local connector.

The invention will be most readily understood from a description of the operation of the system.

The toll operator having been informed, for example, by the recording operator, of the number of the wanted line in the automatic office, tests for an idle trunk by touch-

ing the tip of her plug 100 to the sleeve of the jack 101 of the toll switching trunk and if she does not hear a click in her head set connected to the tip through a normal contact of relay 102 inserts the plug into the jack. The sleeve of the plug applies potential to the sleeve of the jack to cause the seized trunk to test busy at the other toll operators' positions. Relay 102 operates in series with relay F, disconnects the operator's head set and connects the tip of the plug through to the bridged calling supervisory relay 103. Relay 104 is marginal and operates only when the plug is inserted into the jack of a toll line leading to a distant toll switchboard and under such circumstances cuts off the bridge containing relay 103 to prevent this bridge from shunting the alternating current applied by the operator at such distant toll switchboard to operate an alternating current relay (not shown) in the cord circuit. This is in accordance with well-known practice. Relay F in attracting its inner right armature locks itself in series with relay C and in attracting its outer right armature operates relay G. Relay G locks itself in a circuit including the armature and normal contact of relay J, and operates relay H to open the bridge containing relay J. Relay G at its right armatures interconnects the incoming and outgoing ends of the trunk and relay F at its outer and middle left armatures connects the impulse contact 106 of the toll operator's dial 105 through relays D and E to the impulse relay A² of the incoming selector at the distant automatic office. The dial is common to the trunks of the position. Relays A² and D operate in this circuit, but relay E is polarized and does not respond to this direction of current flow. Relay D in closing its contact operates relay B which at its inner armature interposes a break in the circuit of lamp 107. The circuit of this lamp will be closed momentarily when the plug is inserted in the jack but will be opened almost immediately by the operation of relay B which will be energized by the attraction of the armature of relay D if current flows back over the trunk from relay A², thus indicating that the incoming selector at the distant automatic office is ready to receive impulses from the dial. In case,

however, the automatic equipment is not ready for impulses, that is, if current does not flow back through the loop circuit when the dial is connected to the trunk by the 5 operation of relays F and G, relay D will not operate and therefore the armature of relay B will remain retracted, thus permitting the lamp to burn which serves as a guard signal to inform the operator that 10 she should not dial. The lamp will also be lighted when one of the selector encounters a busy trunk group, as will be later described. Relay B at its right armature closes a shunt around the right armature 15 contact of relay A. Relay A² operates the usual slow relay B² which opens the circuit of the release magnet 240 and connects the vertical magnet 210 to the back contact of the impulse relay A² in the well-known 20 manner:

When the operator rotates the dial for the first digit contact 108 closes, operating relay A which in attracting its inner armature locks itself to the front contact of relay 25 C and in attracting its outer armature provides a circuit to hold relay B operated while the armature of relay D is vibrating as the dial restores. Dial 105, in returning to normal, interrupts at its impulse contact 30 106 the circuit of the impulse relay A². Upon each retraction of the armature of relay A², the following circuit is closed for the vertical magnet 210 of the incoming selector: grounded armature 211, and back 35 contact of relay D², conductor 212, armature and back contact of relay A², lower armature and front contact of relay B², slow relay C², vertical magnet 210, and free pole of battery. On the first step of the selector, 40 off normal springs 213 close the following circuit for relay 214: free pole of battery, relay 214, conductor 215, off normal springs 213, conductors 216, 217, armature and front contact of relay C² to ground at the upper armature and front contact of relay B². Relay 45 214 in attracting its upper armature locks itself over the following circuit: free pole of battery, relay 214, conductor 215, off normal contact 213, conductor 216, armature and back contact of rotary magnet 218, conductor 219, upper armature and front contact of relay 214, to ground at the armature 211 and back contact of relay D². Upon the cessation of the 50 impulses relay A² remains energized and consequently relay C² which is slow to release, after an interval releases, whereupon the following circuit is closed to energize the rotary magnet 218 of the selector to 55 step the selector brushes onto the first trunk in the selected level: free pole of battery, magnet 218, conductor 222, lower armature and front contact of relay 214 upper normal contact of relay C², upper armature and front contact of relay B² to ground. At 60

the end of its stroke, the rotary magnet 218 opens the locking circuit traced for relay 214. Relay 214 in retracting its lower armature opens the circuit of the rotary magnet. If the first trunk is busy, ground is 70 present on the test multiple 223 thereof, whereby the following circuit is closed to again energize relay 214: grounded multiple 223, test brush 224, conductor 225, armature 226 and back contact of relay D², conductors 227, 219, back contact and armature of magnet 218, switch 213, conductor 215, relay 214 to free pole of battery. Relay 214 in attracting its upper armature again locks itself through the back contact of the 75 rotary magnet and in attracting its lower armature again closes the circuit of the rotary magnet whereupon the selector brushes are stepped to the next trunk. This interaction of the relay 214 and the rotary magnet is continued until an idle trunk is found which is indicated by the absence of ground 80 on the test multiple 223 thereof. When the rotary magnet, at the end of its stroke, positions the brushes on this idle trunk, no ground being present, relay 214 does not energize but switching relay D² energizes over the following circuit: free pole of battery, relay 214, conductor 215, switch 213, conductor 216, armature and back contact 85 of rotary magnet 218, conductor 219, conductor 227, conductor 228, relay D², conductor 229, lower normal contact of switch 207, conductor 230, to ground at the upper armature and front contact of relay B². Relay 214 is marginal and does not operate in this circuit. Relay D² in attracting its armatures 204 and 201 extends the talking conductors through to the selector brushes 90 and cuts off impulse relay A². 100

Assuming now that the selector has failed to find an idle trunk, on the eleventh rotary step, switch 207 is operated by the shaft of the selector and at its upper contacts 105 opens the circuit of the impulse relay A² which causes the selector (Fig. 2) to restore. The opening of the loop circuit also causes relay D (Fig. 1) to be permanently deenergized. When the dial 105 reaches its normal position after being rotated for the first digit the contact 108 opens one of the 110 circuits traced which circuits have been holding relay B energized and relay D being inert the other circuit for relay B is also open. Relay B thereupon releases, the retraction of its inner armature closing the circuit of lamp 107. This circuit includes the front contact of relay C. The toll operator knows by the illumination of this lamp that the incoming selector has failed to find an idle trunk. If she fails to notice the lighted lamp and operates the dial for the rest of the digits, this has no effect on the switches because the impulse circuit is 115 open at the right armatures of both relays 120 125 130

B and A, the latter relay being locked in a circuit including the front contact of relay C. If it were not for this arrangement the impulses of the second digit would operate 5 the incoming selector and the rest of the digits would operate succeeding switches which would either result in a false connection or useless operation of the switches. Upon noticing the lighted lamp, the operator removes the plug from the jack, releasing 10 the relays F, C, H, and A. Relay G is unlocked when relay J operates in series with relay A² of the incoming selector when the off-normal switch 207 is closed as such 15 selector reaches its normal position.

Assuming, however, that an idle trunk was found, the seizure of the toll transmission selector repeater Fig. 3, in which such trunk terminates, causes the closure of the 20 following circuit for impulse relay A³ thereat, free pole of battery, left hand winding of relay A³, conductor 300, contact 301, of relay B³, conductor 302, contact 303 of relay F³, conductor 309, lower left hand 25 winding of repeating coil 304, conductor 308, multiple terminal 234, brush 233, conductor 232, armature 201 and front contact of relay D², conductors 202, 109, inner right armature and alternate contact of relay G, 30 conductors 110, 111, middle left armature and alternate contact of relay F, relays E and D, impulse spring 106, conductor 112, outer left armature and alternate contact of relay F, conductors 113, 114, outer right 35 armature and alternate contact of relay G, conductors 115, 203, armature 204 and alternate contact of relay D², conductor 252, brush 250, multiple 251, conductor 307, upper left winding of the repeating 40 coil, conductor 305, contact 306 of relay F³, conductor 310, contact 311 of relay B³, conductor 312, left winding of relay A³ switch 313 operated only on the eleventh rotary step of the selector, to 45 ground. The impulse relay A³ in attracting its right armature energizes slow relay 314. This relay in attracting its outer left armature supplies a ground to the test multiples 223 to cause this trunk to test busy. When 50 the relay 314 operates it closes at its right hand armature the following circuit for relay D²: ground, right armature and front contact of relay 314, conductors 315 and 316, contact 317 of relay G³, conductor 318, outer right hand armature and back contact 55 of relay F³, conductor 319, relay D² to free pole of battery.

The second operation of the dial by the operator transmits the corresponding digit 60 of the called line causing relay A³, to transmit impulses over the following circuit to the vertical magnet 320 of the selector repeater: ground, right armature and back contact of relay A³ inner left armature and front contact of relay 314, conductor 321,

armature 322 and back contact of relay G³, conductor 323, slow relay 324, magnet 320 to free pole of battery. The brushes of the selector are thus elevated to the desired level. When the dial returns to normal and maintains 70 the relay A³ energized, after a slight interval, slow relay 324 releases. When the relay 324 operated on the first impulse and the selector took its first step, relay 325 corresponding to relay 214 (Fig. 2) operated 75 over the following circuit: free pole of battery, relay 325, upper contact of off normal switch 325, conductor 327 armature and front contact of relay 324, conductor 390, armature 329 and back contact of relay 330 80 to ground. In attracting its inner armature, relay 325 locks itself, this circuit including the armature and back contact of rotary magnet 331. These circuits are similar to those of the selector of Fig. 2. Upon 85 the cessation of the impulses and the release of the slow relay 324, the circuit of the rotary magnet is closed as follows: free pole of battery, magnet 331, outer armature and front contact of relay 325, normal contact 90 of relay 324, conductor 390, to ground at the armature 329 of slow relay 330. The rotary magnet advances the brushes onto the terminals of the first trunk and at the end of its stroke opens the locking circuit of the 95 relay 325 which releases opening the circuit of the rotary magnet. If the trunk is busy, relay 325 again energizes over the following circuit: free pole of battery, relay 325, upper contact of switch 326, conductor 327, 100 armature and back contact of rotary magnet 331, conductor 333, back contact and armature 334 of relay G³, conductor 335, armature 336 and back contact of relay 330, conductor 337, test brush 338 to ground on the test multiple 339. Relay 325 in attracting 105 its inner armature again locks up and at its other armature again closes the circuit of the rotary magnet which advances the brushes to the next trunk and at the end of its stroke opens the locking circuit of relay 325 which in retracting its armature opens the circuit of the rotary magnet 331. The switch 313 corresponds to the switch 110 115 207 of the incoming selector circuit, Fig. 2. Its function is to permanently open the circuit of the impulse relay A³ on the eleventh rotary stop of the selector, that is to say, if all the trunks in the group are busy. The opening of this circuit releases slow relay 314 which in retracting its outer left armature releases relay D² of the incoming selector. Relay D² in retracting its armature 120 effects the operation of release magnet 240 whereupon the incoming selector switch is restored to normal. Relay 314, in retracting its inner left-hand armature closes a circuit for release magnet 383 whereupon the selector repeater (Fig. 3) 125 releases. In releasing its armature 201, re- 130

lay D^2 opens the circuit for relay D (Fig. 1) whereupon the all trunk busy lamp 107 (Fig. 1) is illuminated as previously described. If, however, an idle trunk is found, relay G^3 which corresponds to relay D^2 , Fig. 2 operates over the following circuit: free pole of battery, relay 325, upper contact of switch 326, conductor 327, armature and back contact of magnet 331, conductor 333, relay G^3 , conductor 340, upper contact of switch 313, conductors 341, 315, to ground at the right armature and front contact of relay 314. Relay 325 is marginal and does not operate in this circuit in series with the relay G^3 . Relay G^3 operates and in attracting its armatures 342 and 343 extends the talking conductors through to the talking brushes 344 and 345. The attraction of the armature 334 of relay G^3 grounds the test brush 338 and consequently test multiples 339 of the selected trunk, causing the same to test busy to other selectors. The contact 346 is made before the contact 317 is broken by the armature 347 of the relay G^3 . Consequently relay D^3 is maintained energized over the following circuit: free pole of battery, relay D^3 , conductor 319, outer right armature and back contact of relay F^3 , conductor 318, contact 346, armature 347, conductor 348, brush 349, multiple 350, control conductors 351, 400, (Fig. 4), conductor 401, armature 402 and back contact of relay K^4 , conductor 403, sleeve conductor 450, conductor 352, multiple 339, brush 333, conductor 337, armature and back contact 336 of relay 330, conductor 335, armature 334 and front contact of relay G^3 conductor 315, to ground at the right armature and front contact of slow relay 314. Thus, the circuit for relay D^3 (Fig. 3) is maintained closed as the circuit is extended. The switch of Fig. 4 to which the connection has been extended is a combination toll and local connector containing multiples of ordinary automatic subscribers lines in its bank. This switch is accessible not only to the selector-repeaters of Fig. 3, but also to the local selectors which are used by the subscribers in building up their own connections. The seizure of the connector causes the closing of the following circuit for the impulse relay A^4 : free pole of battery, upper winding of relay A^4 , conductor 404, contact 475 of relay D^3 , conductor 405, left winding of slow relay J^4 , conductor 407, lowermost armature and back contact of relay K^4 , ring conductor 446, conductor 353, multiple 354, brush 345, conductor 355, armature 343 and front contact of relay G^3 , left armature and front contact of relay A^3 , ring conductor 357, armature 356 and back contact of relay H^3 , conductor 358, lower right hand winding of the repeating coil 304, resistance 359, conductor 360, inner left armature and front contact of relay D^3 , left winding of relay 361, conductors 362, 363, resistance 364, upper right hand winding of repeating coil 304, conductor 365, upper armature and back contact of relay H^3 , uppermost armature and front contact of relay G^3 , brush 344, multiple 367, tip conductor 410, upper armature and back contact of relay K^4 , conductor 476, back contact 477 of D^4 , lower winding of relay A^4 to ground. When relay G^3 (Fig. 3) operates a circuit is also closed through the right hand winding of relay 361 which leads over 376, 370, armature 334 and front contact of G^3 , conductor 315, to ground at the armature and front contact of relay 314. The current in the circuit just traced is opposite in direction to that in the left hand winding of this relay. Consequently this relay does not operate at this time. Relays J^4 and A^4 operate, however, the former at its innermost right armature closing a locking circuit for itself as follows: free pole of battery, right winding and right innermost armature and front contact of J^4 , conductor 431, conductor 415, to ground at the armature 416, and front contact of slow relay B^4 which is energized upon the energization of the impulse relay A^4 . Relay B^4 grounds the sleeve wire 417, leading to the test multiples in the local selectors, this circuit leading from grounded armature 416, conductor 415, to conductor 417. The return of the dial to normal in transmitting the tens digit of the wanted number interrupts the circuit of relay A^4 , which in vibrating its armatures transmits impulses to the vertical magnet 418 of the connector. The circuit for the first impulse is as follows: free pole of battery, magnet 418, slow relay 419, right contact of off normal switch 420, conductor 421, lower armature and front contact of relay B^4 to ground at the armature and back contact of the impulse relay A^4 . At the first step of the connector, the off normal springs 420 are shifted and the succeeding impulses are transmitted by way of the upper armature and front contact of relay 419 and the contact 422 now closed at the off normal springs 420. Relay F^4 is operated by its lower winding when relay 419 operates, this circuit including the innermost right armature of relay J^4 and grounded armature 416 of relay B^4 . Relay F^4 locks up to the sleeve wire 450 in a circuit including armature 402. The connector brushes are thus lifted to the desired level and upon the cessation of the impulses, impulse relay A^4 remains energized and relay 419 in series with the vertical magnet releases preparing the circuit of the rotary magnet 423. The units impulses pass through the back contact of the impulse relay A^4 , lower armature and front contact of relay B^4 , conductor 421, off normal contact 422, back contact of slow relay 419, con-

ductor 424; innermost left armature and front contact of relay G⁴, conductor 425, uppermost armature and back contact of relay H⁴, rotary magnet 423 to free pole of battery. The connector is thus stepped around into engagement with the desired line.

If this line is idle, full potential is present on its test multiple 426 through the 10 ect off winding of the line switch, and the following circuit is closed to operate relay H⁴: multiple 426, brush 427, conductor 428, armature 440 and back contact of relay E⁴, conductor 429, upper winding of relay H⁴, conductor 430, right hand armature and back contact of relay G⁴, conductor 431, conductor 415, armature 416 of relay B⁴ to ground. Relay H⁴ in attracting its armature 532 locks itself to the grounded sleeve 20 wire 450 and extends this grounded conductor over conductor 433, middle right armature and front contact of relay J⁴, conductor 434 to the relay K⁴. Relay K⁴ in attracting its armature 402 disconnects the 25 grounded sleeve wire 450 from the control lead 400 leading back to the relay D³, Fig. 3 of the selector repeater. Relay D³ in retracting its outer left hand armature operates relay F³, to reverse the current flow in 30 the circuit leading back to the operator's cord to energize relay 103 to light the lamp 117 (Fig. 1) as a ringing signal to the toll operator. The circuit for relay F³ is as follows: free pole of battery, relay F³, conductor 369, outer left armature and back contact of relay D³, conductor 370, armature 334 and front contact of relay G³, conductor 315 to ground at the right armature and front contact of relay 314. Relay F³ 35 in attracting its outer right armature applies the following substitute ground to hold up the relay F⁴ before it can release in order to prevent ringing from occurring at this time as would occur if this relay released: 40 ground, left hand armature and back of relay 371, conductor 372, outer left armature and back contact of relay B³, outer right armature and front contact of relay F³, control conductor 318, contact 346 and armature 347 of relay G³, conductor 348, brush 349, multiple 350, conductor 351, conductor 400, front contact and armature 435 and lower winding of relay F⁴ to free pole of battery. The operation of relay K⁴ by 45 releasing D³ and operating F³ which caused the reversal of direction of the current flow in the loop leading back to the toll operator's position opens the locking circuit of relay F⁴ and unless a substitute circuit is 50 provided for holding up relay F⁴ as just described, after relay K⁴ operates the ringing operation would automatically take place as will appear. This is prevented by applying ground to the control conductor 400 over the circuit traced to hold the

relay F⁴ until the operator, by depressing a key as will be explained, releases relay F⁴ to start the automatic ringing operation. The release of the relay D³ and the consequent energization of relay F³ as described 70 reverses the direction of current flow in the talking conductors leading back to the operator's position. This reversal operates polarized relay E (Fig. 1) which releases relays F and C which in deenergizing disconnects the dial from the trunk 110, 114 and connects the trunk through to the calling supervisory relay 103 which now operates in series with the impulse relay A⁴ of the connector. Relay 103 in operating lights 75 the calling supervisory lamp 117 as a signal to the toll operator that the line desired was found idle by the connector. Relay F also releases relay D. Relay A unlocked when relay C released. Relays E, C, D, A and B 80 are individual to the dial and common to the trunks at a position. Relays F, J, H and G are individual to a given trunk. The operator now operates ringing key RK which 85 impresses alternating current upon the talking conductors which operates the alternating current relay C³ which in attracting its armature operates the relay 371. This relay in attracting its left armature opens the 90 circuit heretofore traced, which has been holding relay F⁴, Fig. 4, energized. This relay in retracting its armatures 437, 499 connects ringing current to the called line 95 through its upper winding. This ringing current is automatically intermittently applied 100 until the called party removes his receiver, resulting in an increase in the current through the upper winding of relay F⁴ causing the same to operate removing the ringing current. The attraction of the 105 armature 435 of this relay closes a locking circuit for the same over grounded control conductor 400. The extension of the tip and ring conductors by relay F⁴ to the called line operates relay 373 over which 110 talking current is fed to the called line. Relay 373 in operating energizes relay B³ which in attracting its outer left hand armature applies ground to the conductor 374, and outer right armature of relay F³, conductor 318, contact 346, armature 347 of 115 relay G³, conductor 348, brush 349, multiple 350, conductors 351, 400, front contact and armature 435 of relay F⁴, lower winding of relay F⁴ to battery, to hold up relay F⁴ 120 independently of relay 371. Relay B³ in opening its contacts 311, 301 opens the connection of battery through the windings of relay A³ to the talking conductors 307, 308, leading back to the toll operator's position 125 which causes the deenergization of supervisory relay 103. This relay in retracting its armature extinguishes the supervisory lamp 117 which notifies the operator that the subscriber has responded. Talking cur- 130

rent is fed to the called line over the winding of relay 373 and the repeating coil 304. This talking circuit is a standard repeating coil transmission circuit used in long distance connections. Talking current is fed to the calling line from the distant exchange. During conversation the trunk leading from the left hand windings of repeating coil 304 through the right hand winding of the repeating coil (not shown) at the distant office, is dry, in accordance with standard practice.

Assuming now that the desired line when selected by the connector is busy, the test multiple 426, Fig. 4, is grounded. When test wiper 427 is set on the busy multiple 426, ground is extended over brush 427, conductor 428, armature 440, contact 444 of relay E⁴, conductor 441, armature 442 and back contact of relay H⁴, conductor 443, relay G⁴ to free pole of battery. Relay G⁴ energizes and when slow relay E⁴ releases, locks itself up over the following circuit: free pole of battery, relay G⁴, conductor 443, armature 442 and back contact of relay H⁴, conductor 441, make before break contact 498 of relay E⁴, right armature and front contact of relay G⁴, conductor 431, conductor 415 to ground at the armature 416 and front contact of relay B⁴. Relay G⁴ in the case of a local call connects busy tone from the source 445 to the calling line. In the case of a toll call this busy tone is not used, a flashing signal being given to the operator instead. Relay G⁴ in operating due to the line being busy prevents test relay H⁴ from operating when slow relay E⁴ releases. When busy test relay G⁴ operates a circuit is closed for relay D⁴ from free pole of battery, upper winding of D⁴, conductor 478, conductor 479, contact 480 of relay K⁴, conductor 481, resistance 490, armature 482 and back contact of relay E⁴, outer left armature and front contact of G⁴, inner right armature of relay J⁴ and front contact, conductor 431, 415 to ground at armature 416 and front contact of B⁴. Relay D⁴ reverses the direction of current flow through the left winding of relay 361 (Fig. 3) which results in this relay operating. The left armature and front contact of relay 361 closes a circuit for operating relay F³ as follows: battery, relay F³, conductor 369, left armature and front contact of relay 361, conductors 376, 370, armature 334 and front contact of G³, conductor 315 to ground on the right armature and front contact of relay 314. Relay F³ reverses the direction of current flow in the circuit leading back to the operator's cord as in the case of an idle line to operate polarized relay E which in turn releases relay F to connect the talking conductors of the cord through to the connector and also releases the common relays E, C, D and A as in the case of a free line.

The right armature of relay 361 connects interrupter 379 to relay 371 which in operating intermittently applies ground to conductor 300 in shunt of the circuit leading over tip conductor 307 back to the operator's cord. The circuit of relay 371 leads over the outer right back contact of relay D³ to ground at the right armature of relay C³. The intermittent ground applied to conductor 300 by relay 371 shunts out the relay 103 intermittently which causes the flashing of the lamp 117. The operator thus knows that the desired line is busy and removes the plug from the trunk switching jack. This causes the release of all switches and the return to normal condition of all the apparatus including the various locked up relays.

During the conversation the called subscriber by moving his hook up and down causes the supervisory lamp 117 at the toll operator's position to flash as in the case of manual telephone exchange practice, without releasing the switches. This is apparent from the preceding description inasmuch as relay 373 is in circuit with the called line and each time it attracts its armature operates the relay B³ which removes battery and ground from the trunk conductors leading back to the supervisory relay 103 and places a bridge across the relay A³ to hold it operated to prevent release of the switches. When the called subscriber replaces his receiver the lamp 117 lights at the toll operator's position, Fig. 1.

The operator may re-ring the subscriber after he has replaced his receiver if she desires to recall him by actuating her ringing key RK, which operates relay C³ to operate 371 which in attracting its left hand armature again releases relay F³ which initiates the automatic ringing operation at the connector. The control of this relay F³ was removed from the relay 371 by the attraction of the outer left armature of relay B³ when the called subscriber responded and was restored to the relay 371 and consequently to the operator when the called subscriber replaces the receiver and deenergizes relay B³.

When the operator desires to break down the connection after the called subscriber has replaced his receiver, she removes the plug from the toll switching jack. This releases relay A³, Fig. 3, which causes the restoration of all the switches. If, however, the operator removes the plug while the called subscriber still has his receiver off the switch hook, the switches are not released since relay A³ which controls the release is maintained energized over the following circuit: battery, left hand winding of relay A³, conductor 300, armature 380 and front contact of B³, resistance 381, conductor 312, right hand winding of relay A³ to ground at the lower normal contact of

switch 313, it being noted that the relay B³ which controls this loop circuit is itself controlled by relay 373 in circuit with the called line and controlled at the switch hook 5 of said line.

The withdrawal of the plug before the called party has restored his receiver disconnects the battery supplied through relay 102 and the sleeve of the plug from the 10 sleeve multiples of the jacks of this trunk at the other toll positions but relays J, G and H cooperate to place potential thereon in the following manner: when the plug was inserted in the jack and relay F operated, 15 it closed a circuit to operate relay G as described. Relay G then locked itself to battery at the right armature of relay J. Relay J is inert at this time since relay H operated when relays F and G operated. 20 Relay H at its left armature opened the circuit of relay J to prevent the bridge including said relay from interfering with the impulses to the switch. After relay F is released due to relay E operating when 25 the called party answers, relay H is held operated from battery on the sleeves of the plug and jack to hold open the bridge containing relay J. When however, the plug is removed while the calling party 30 still has his receiver off the switchhook relay H releases and relay J being inert due to the trunk 115, 109 being dry, relay G is held locked to battery at the right armature of relay J. Battery is thus supplied over the following path to the sleeves 35 of the jacks: right armature and back contact of relay J, innermost left armature and front contact of relay G, conductors 118, 119, right armature and back contact of relay H, resistance 120, middle left armature and front 40 contact of relay G, conductor 121, innermost left armature and back contact of relay F, conductor 122 to the sleeve multiples. Relay G is locked in a circuit including the 45 same armature of relay J. When the called party replaces his receiver battery is applied to the trunk 115, 109 as described and relay J operates, unlocking relay G thus removing the busy condition from the jacks 50 of this trunk at all the toll positions at which they appear.

Assuming, however, that the called subscriber has replaced his receiver, when the operator removes the plug, relay A³ in releasing deenergizes slow relay 314. Relay 55 314 in retracting its outer left armature removes ground from the sleeve conductor 382 leading to the release relay D² whereupon this relay closes the circuit of release magnet 240 as follows: free pole of battery, magnet 240, off normal switch contact 213, lower armatures and back contacts of relay B² and A² to ground at the armature 211 60 and back contact of relay D². Thus the first selector is restored and upon reaching 65

its normal position opens the off normal springs 213. The removal of ground from conductor 315, by the retraction of right hand armature of relay 314 releases relay G³ and the retraction of the right hand 70 armature of relay A³ and inner left armature of relay 314 closes a circuit for the release magnet 383 at the selector repeater. The slow relay 330 is energized in parallel 75 with the release magnet and opens the circuit to the test brush 338 during restoration at its armature 336, to prevent interference with other connections. At its armature 384 it short circuits the right hand winding 80 of relay A³. At its armature 329 it closes a locking circuit for itself which is opened 85 when the off normal switch 326 assumes its normal position. The opening of the circuit of the tip and ring conductors 410, 446 causes the release of relays A⁴, B⁴, J⁴, Fig. 4, which results in the closure of the 90 following circuit for connector release magnet 440: free pole of battery, magnet 440, left hand contact of off normal switch 420, back contact and lowermost armature 483 95 of relay D⁴, lower armature and back contact of relay B⁴ and A⁴ to ground. The connector upon reaching normal position restores the off normal switch 420.

What is claimed is:

1. In a telephone system, the combination at an operator's position of trunks terminating thereat, an impulse sender, a signal means for connecting the impulse sender with any one of said trunks and for actuating said signal, and means for maintaining said signal operated in case a trunk with which the sender is connected is in an unstandard condition.

2. In a telephone system, the combination at an operator's position of trunks terminating thereat, cord circuits at said position, an impulse sender, a signal device, means for connecting said sender with one of said trunks and for actuating said signal device in response to the connection of one of said cord circuits with said trunk, an electromagnetic means responsive to a predetermined electric condition of said trunk when it is ready to receive impulses from said sender for effacing said signal, and means for maintaining said signal operated in case said predetermined electric condition is not present on the trunk.

3. In a telephone system, the combination at an operator's position of trunks terminating thereat in jacks and at the other end in automatic switches, cord circuits at said position, a signal circuit including a signal device, an impulse sender common to said trunks, means for connecting said sender with one of said trunks responsive to the insertion of a plug of one of said cord circuits in the jack of said trunk, electromagnetic means responsive to the insertion of

said plug in said jack for closing said signal circuit, means responsive to current flow in said trunk for opening said signal circuit, and means for maintaining said signal circuit closed in case a trunk is in condition to prevent current flowing thereover.

4. In a telephone system, the combination with a plurality of trunks terminating at an operator's position of an impulse sender, means for associating said sender with any one of said trunks responsive to the seizing of said trunk, a signal for each trunk, an operating circuit therefor established in response to the connection of the sender to the corresponding trunk, and means for maintaining said signal circuit established in case a condition exists on the seized trunk that prevents the transmission of impulses thereover.

5. In a telephone system, the combination with a plurality of trunks, switches in which said trunks terminate at an operator's position, an impulse sender, means for associating said sender with any one of said

trunks responsive to the seizing thereof through one of the corresponding switches, a signal associated with each of said trunks, an operating circuit for each of said signals established in response to the seizing of the corresponding trunk, and means for maintaining the operating circuit of the seized trunk established responsive to an unstandard condition of said seized trunk.

6. In a telephone system, trunks, a sender common to said trunks, a signal for each trunk, means responsive to the seizing of any one of said trunks for connecting the sender therewith and for actuating the corresponding signal, means responsive to a standard condition on said seized trunk for restoring said signal to normal, and means responsive to an unstandard condition on said seized trunk for maintaining said signal actuated.

In witness whereof, I hereunto subscribe my name this 19th day of March A. D., 1924.

RAY L. STOKELY.
